LINE LATCH

Myron M. Kinley, Los Angeles, Calif., assignor to
John C. Kinley

Filed Aug. 15, 1958, Ser. No. 755,231

8 Claims. (Cl. 24—134)

This invention relates to new and useful improvements in line latches.

In well drilling and other operations, well tools and other devices are often supported and manipulated by a flexible line or cable, such as a wire line, electric line, sand line, drilling lines, or other similar lines, and in some instances such tools or devices become stuck or lodged in the well bore so that it is impossible to retrieve the tool or device by pulling on the flexible line. It then becomes necessary to sever the line at an inaccessible point in the well bore to salvage the line. When the line is severed, it becomes possible to either attach some other type of fishing tool to the stuck tool or device for retrieving such tool or device from the well bore, or to remove the stuck tool or device by pulling the tubing or pipe in which the stuck tool or device is located.

One type of cutting tool for severing the wire line under the above circumstances is illustrated in U.S. Patent 2,794,619, issued June 4, 1957.

An object of this invention is to provide a new and improved line latch which is particularly suitable for engaging a wire line or other flexible line in a well which is cut by a cutting tool.

Another object of this invention is to provide a cutting tool for a flexible line having a new and improved means for latching or gripping the flexible line cut by the cutting tool.

A further object of this invention is to provide a new and improved line latch which has a means that is adapted to be moved substantially laterally into engagement with a flexible line for applying an efficient gripping action on the line.

A particular object of this invention is to provide a new and improved line latch for gripping a flexible line, wherein a pivoted gripping or latching member is adapted to be urged into gripping engagement with the flexible line.

Still another object of this invention is to provide a new and improved line latch for gripping a flexible line in a well, wherein the latch is adapted to be actuated simultaneously with the actuation of a cutting tool for the flexible line by either dropping a weight in the well or by using a time delay mechanism for actuation.

A further object of this invention is to provide a new and improved line latch or gripping structure wherein an actuator member is wedged between a stop member and a gripping member when the gripping member is in engagement with the line so that the reaction forces from the gripping engagement between said gripping member and said line act in a substantially lateral direction on said actuator member, whereby there is substantially no tendency of the actuator member to move longitudinally away from its position in which it is urging the gripping member into gripping engagement with said line.

Still a further object of this invention is to provide a new and improved line latch for gripping engagement with a line, wherein an actuator member is wedged between a gripping member and a stop member, and wherein the stop member is movable to pull a back-up sleeve in a direction towards the gripping member as the actuator member is wedged between the stop member and the gripping member, whereby an increased gripping engagement on the line is obtained.

The preferred embodiment of this invention will be described hereinafter, together with other features there-

2

of, and additional objects will become evident from such description.

The invention will be more readily understood from a reading of the following specification and by reference to 5 the accompanying drawings forming a part thereof, wherein an example of the invention is shown, and wherein:

FIG. 1 is an elevation, partly in section, illustrating one form of the tool of this invention;

FIG. 2 is a view, partly in section and partly in elevation, illustrating the upper portion of the tool shown in FIG. 1 to illustrate in particular the improved latch or gripping mechanism of this invention in its position prior to gripping engagement with the flexible line;

FIG. 3 is a horizontal sectional view taken on line 3—3 15 of FIG. 2;

FIG. 4 is a perspective view of the actuator member which is preferably used in the line latch or gripping mechanism of this invention as illustrated in FIGS. 2—4 in particular;

FIG. 5 is a view similar to FIG. 2, except that it shows 20 the line latch or gripping mechanism in a gripping position; and

FIGS. 6A and 6B are views, partly in elevation and partly in section, which illustrate a modified form of the 25 tool of this invention wherein a time delay mechanism is utilized for actuating same.

In the drawings, the letter A designates generally the cutting tool of this invention which is adapted to be dropped into a well bore, well pipe or casing C along a 30 flexible line F. The flexible line F may be a wire line, sand line, electric line, drilling line or any other flexible line, particularly those lines which are located in a well bore casing or other well pipe. Generally, the flexible line F is connected to a well tool with a rope socket 10, 35 and because the well tool (not shown) has become stuck in the well bore or casing C, the tool A is used for cutting the flexible line F and for gripping the cut portion of the flexible line F above the point at which the line F is cut so that the tool A may be retrieved from the well bore or casing C by lifting the flexible line F upwardly. The tool A has a tubular elongate body 11 which is preferably formed in several parts, and which has mounted therewith a cutting means and a gripping means to accomplish the cutting of the flexible line F and the gripping thereof. As will be explained more in detail, the cutting means includes a cutting knife 12 and other structure which is substantially identical with the cutting means disclosed in the said United States Patent No. 2,794,619. The gripping means, as will be explained, includes a gripping member 14 which is adapted to be moved substantially laterally without any appreciable longitudinal movement thereof for gripping engagement with the flexible line F after it has been cut by the knife 12.

Considering the invention in detail, it should be pointed out that the cutting means of the tool A has been illustrated in sufficient detail to show its relationship to the new and improved latch or gripping mechanism of the tool A, and further details of the cutting means are shown in said Patent No. 2,794,619. The cutter knife or blade 12 is held against movement by a shear pin 15, but upon the shearing or severing of such pin 15, the knife 12 moves from its position in the lower bore portion 11a of the body 11 through an opening 11b in the body 11 to cut through the flexible line laterally. The cutter blade or knife 12 is moved laterally and the shear pin 15 is initially sheared by the downward movement of a wedge member 16 which has an inclined or wedge surface 16a thereon which moves behind the knife 12 to force same through the opening 11b for cutting the flexible line F. The downward movement of the wedge member 16 in the bore 11a of the body 11 is limited by con-

tact with a stop member 17 which has an inclined face 17a which has substantially the same inclination as the inclined surface 16a. The stop member 17 is integral with the body 11 or is secured thereto by any suitable means such as a removable bolt 18. The wedge member 16 is moved downwardly by the force of an explosion of an explosive powder 20 confined above the wedge member 16 as shown in FIG. 1 of the drawings. A percussion cap or firing cartridge 21 such as a shotgun shell is mounted above the powder 20 and it is actuated by a blow or impact from a striking member or firing pin 22. Preferably, an additional rubber seal 21a surrounds the cartridge 21 to prevent fluid from passing to the explosive powder 20. The firing pin 22 is formed with a tapered external surface which fits within a correspondingly tapered portion 11c of the body 11 so that upward movement of the firing pin 22 is limited, but downward movement thereof for the striking of the cartridge 21 is permitted. Downward movement is imparted to the firing pin 22 through a longitudinally movable actuating rod 24 and an impact head 25 which is also longitudinally movable with respect to the body 11. Preferably, the rod 24 and the head 25 are separate from each other and are separate from the firing pin 22, but they may be formed or connected together if desired. In the form of the invention shown in FIGS. 1-5, the impact head 25 is engaged by a weight W (FIG. 1 and FIG. 5) which is dropped in the well bore or casing C so as to strike the impact head 25. The head 25 has a longitudinal groove 25a for receiving a screw 27 or other suitable means to limit the rotational movement of the head 25 and to prevent an inadvertent removal of the head 25 from the body 11.

With regard to the improved latch or gripping mechanism of this invention, the gripping member 14 is mounted in a lateral window or opening 11d of the body 11. The gripping member 14 is mounted for pivotal movement about a pivotal connection pin or rod 29 which extends from the longitudinally extending walls on each side of the opening or window 11d through a pivot hole 14a formed in the gripping member 14. The member 14 may be formed in one piece or it may be formed of a plurality of pieces which are welded or otherwise secured together as illustrated in FIG. 3. The member 14 is provided with an outer surface 14b and a lower surface 14c which come together and form a relatively sharp point 14d which is adapted to engage and embed itself into a portion of the flexible line F in gripping engagement therewith, as will be explained in detail. As the tool A is being lowered into the well on the flexible line F, and prior to the actuation of the gripping member 14 into gripping engagement with the flexible line F, the member 14 is held in a retracted non-gripping position (FIG. 2) by a retaining pin 30 which extends through an opening 14e in the gripping member 14. In such retracted non-gripping position of the member 14, the outer surface 14b is positioned substantially vertically or in alignment with the external surface of the body 11 as seen in FIG. 2 so that the pointed portion 14d of the member 14 does not project outwardly from the window or opening 11d.

The slidable rod 24 which is positioned in the upper bore portion 11e of the body 11 is preferably formed with a reduced diameter portion 24a at its upper end. An actuator member 35 has a bore or longitudinal opening 35a therethrough. In the preferred form of the invention, the actuator member 35 is substantially cylindrical as indicated at 35b (FIG. 4) except for two flat inclined or tapered wedge surfaces 35c and 35d. The actuator member 35 is mounted on the reduced diameter portion 24a of the rod 24, with the reduced diameter portion 24a extending through the bore 35a of the member 35. A releasable attaching means such as a shear pin 36 extends through the rod portion 24a and the actuator member 35 to releasably position the member 75

35 on the reduced diameter portion 24a of the rod 24 (FIG. 2). Upon a shearing or severing of such pin 36, the member 35 is then free to move longitudinally with respect to the rod 24.

5 A spring 38 or other resilient means is provided on the rod 24 and it is confined between an annular laterally extending shoulder 24b and the lower surface of the actuator member 35. Prior to the actuation of the gripping member 14, the actuator member 35 is held in a fixed position 10 on the rod 24 by the releasable shear pin 36 and in such position, the spring 38 is under compression between the shoulder 24b and the lower end of the actuator member 35. Therefore, when the shear pin 36 is released, the spring 38 urges the actuator member 35 upwardly with respect to the rod 24 (FIG. 5).

The upwardly and inwardly inclined or tapered surface 35c on the actuator member 35 is in engagement with the lower inner surface section 14f when the gripping member 14 is in its retracted non-gripping position 20 and the actuator member 35 is in its position connected to the rod 24 with the releasable pin 36. The surface section 14f is inclined so that it conforms substantially to the inclination of the surface 35c when the gripping member 14 is in its retracted non-gripping position as best seen in FIG. 2. The upper section 14g of the inner surface of the gripping member 14 is inclined so that it has substantially the same inclination as the inclined surface 35c of the actuator member 35 when the gripping member 14 has been pivoted or moved outwardly to its gripping position (FIG. 5).

30 In order to stop the upward movement of the actuator member 35 and to also wedge the actuator member 35 against the gripping member 14 when it has been moved to the gripping position, a stop member 40 is provided in the bore portion 11e of the body 11 at a position substantially laterally opposite from the gripping member 14. The stop member 40 is provided with an inclined surface 40a which has substantially the same upward and inward inclination as the upwardly and inwardly inclined surface 35d on the actuator member 35. Therefore, when the actuator member 35 has reached its upper position wherein it has its inclined surface 35c in contact with the inner surface section 14g of the gripping member 14, the actuator member 35 is wedged between the surfaces 40a of the stop member 40 and the surface 14g of the gripping member 14. In such position, the spring 38 is exerting an upward force on the actuator member 35. The reaction force caused by the tendency of the flexible line F to move the pivoted gripping member 14 about its pivot connection 29 is directed in a substantially lateral or horizontal direction towards the actuator member 35 so that there is substantially no component of force acting on the actuator member 35 in opposition to the spring force from the spring 38. 40 Therefore, when the actuator member 35 has wedged itself between the stop member 40 and the gripping member 14 as shown in FIG. 5, the spring 38 can readily hold the actuator member 35 in its upper position and therefore there is substantially no tendency for the gripping member 14 to force the actuator member 35 downwardly. 45 In fact, the reaction force caused by the gripping engagement of the gripping member 14 with the flexible line F would tend to exert a somewhat upward force on the member 35 because of the location of the pivot pin 29 above the pointed contact end or point 14d of the member 14. Thus, as the reaction force on the gripping member 14 acts on the member 14 to move same away from the flexible line F, the gripping member 14 would tend to swing in a downward clockwise arc about the pin 29 and since the surface 14g is of substantially 50 the same inclination as the surface 35c, that would tend to exert an upward force on the actuator member 35 which would act in the same direction as the spring 38. However, since the surface 14g and the surface 35c are flat surfaces, such upward movement of the actuator 55

member 35 cannot be accomplished and therefore the actuator member 35 remains in a locked wedged position behind the gripping member 14.

In the preferred form of the invention, the tool A of this invention is slidably attached to the line F by lower guide sleeve 45 (FIG. 1) and upper guide sleeve 46 (FIGS. 1-3 and 5). The sleeve 45 serves as a back-up member during the cutting of the line F with the cutter member 12, and similarly, the sleeve 46 serves as a back-up member to confine the flexible line F during the gripping action with the gripping member 14.

For increasing the effectiveness of the gripping action of the gripping member 14 on the line F, the stop member 40 is connected with the sleeve 46 by means of a screw 47 or other fastening means, and the stop member 40 and the sleeve 46 are laterally movable together. The member 40 is formed with a flange 40b which engages the vertical flat surface 11f formed on the body 11 adjacent to the bore 11e. The inner portion of the member 40 extends through an opening 11g in the body 11 as best seen in FIG. 3 of the drawings and the contact of the flange 40b with the surface 11f limits the inward movement of the member 40 towards the actuator member 35. However, the member 40 is movable laterally away from the actuator member 35 as the member 35 moves upwardly relative to the member 40 with the surfaces 35d and 40a in contact with each other. During such lateral movement of the member 40, an upper surface 40c of the member 40 is in sliding contact with the upper wall 11p of an opening in the body 11 and a lower surface 40d of the member 40 is in contact with a lower wall 11r. The sides of the sleeve or band 46 slide along flattened body surfaces or grooves 11m and 11n (FIG. 3) as the member 40 is moved laterally. If desired, the band may be formed of a resilient metal or other material which engages the surfaces 11m and 11n with sufficient friction to normally prevent the lateral movement of the member 40 from its inner position (FIG. 2) until it is urged laterally by the actuator member 35 to the gripping position of FIG. 5.

In connection with the retaining member or pin 39 and a retaining member or pin 36, it should be pointed out that the pin 39 may be omitted because the weight of the gripping member 14 may serve to hold it in the retracted non-gripping position of FIG. 2. Such pin 39 is of course sheared upon the upward movement of the actuator member 35 relative to the gripping member 14 if such pin 39 is employed. The shear pin 36 may take numerous forms, but as illustrated in the drawings, it serves to hold the actuator member 35 in position on the reduced diameter portion 24a of the rod 24 until such time as the pin 36 is severed or sheared. For this purpose, the body 11 is provided with a shoulder 11h which is adapted to be engaged by the lower end of the actuator member 35 upon a downward movement of the rod 24 so as to cause the rod 24 to move relative to the member 35 for shearing the pin 36.

In the operation or use of the form of the invention illustrated in FIGS. 1-5, the tool A is positioned on the flexible line F at the surface of the well with the flexible line F extending through the guide sleeves 45 and 46. The tool A is then dropped in the well bore or casing C and it is guided downwardly on the flexible line F. When the tool A has reached a position in the vicinity of the lower end of the flexible line F, generally in contact with the rope socket 10, a weight W is dropped in the well bore or casing C for imparting a downward impact or blow to the impact head 25. Such impact causes the head 25 to move from the position shown in FIGS. 1 and 2 to the position shown in FIG. 5. The downward impact from the weight W is transmitted through the rod 24 to the firing pin 22 and thus a blow is imparted to the firing cartridge 21 which causes the powder 20 to explode. The explosion from the explosive powder 20 forces the plunger or wedge member 16 downwardly

for initially shearing the pin 15 and for moving the knife 12 laterally through the flexible line F to cut the line F. The downward movement of the plunger or wedge 16 is stopped when the surfaces 16a and 17a are in contact.

Substantially simultaneously with the firing of the explosive powder 20 and therefore the cutting of the line F, the gripping member 14 is actuated to move same into gripping position with the flexible line F. Thus, when the rod 24 is moved downwardly in the body 11 by reason of the downward movement imparted thereto from the impact head 25, the shear pin 36 is severed or sheared due to the fact that the lower end or bottom surface of the actuator member 35 is prevented from moving downwardly by its contact with the annular inwardly extending shoulder 11h of the body 11. Therefore, the relative downward movement of the rod 24 with respect to the actuator 35 releases the shearing pin 36 and the actuator member 35 is then free to move longitudinally with respect to the rod 24 and the body 11. Since the spring 38 is under compression, the spring 38 acts to urge the actuator member 35 upwardly as soon as the pin 35 is sheared or released. The initial upward movement of the actuator 35 forces the gripping member 14 to pivot about its pivot 29 with a sufficient force to shear the shearable retainer pin 30. Thereafter, the gripping member 14 moves substantially laterally and without any appreciable longitudinal movement about its pivot pin 29 so that the point 14d is caused to engage in gripping engagement with the flexible line F. The surface 35c moves in sliding engagement with the surface section 14f at the inner or rear portion of the gripping member 14, and when the gripping member 14 has reached its gripping position, the surface 35c is in substantially complete engagement with the upper inner surface section 14g of the gripping member 14. Also, at that time, the surface 35d of the member 35 is in engagement with the inclined surface 40a of the stop member 40 so as to wedge the actuator member 35 between the stop member 40 and the gripping member 14. Since, as previously explained, there is substantially no force acting on the actuator member 35 to move same in a downward direction, the spring 38 effectively holds the member 35 in its wedged position between the stop member 40 and the gripping member 14 to assure an effective gripping action on the flexible line F. Also, the stop member 40 is moved laterally away from the actuator member 35 which pulls the sleeve or band 46 towards the gripping member 14 to apply a positive back-up force on the line F so as to counteract the tendency of the line F to move away from the member 14 as it engages same. When the actuator member 35 has reached its upper position (FIG. 5), it is therefore exerting a force on the gripping member 14 in one direction and a force on the sleeve 46 in the opposite direction so as to squeeze the line F between the gripping member 14 and the sleeve 46. The tool A is thus effectively latched or gripped with the flexible line F and it may therefore be retrieved from the well bore or casing C by raising upwardly on the flexible line F.

The tool A of this invention may be actuated by a time delay mechanism in the well instead of the dropping of a weight as explained in connection with FIGS. 1-5. In FIGS. 6A and 6B, the tool A of this invention has been modified to show its use with a time delay mechanism. The type of time delay or trip mechanism which is illustrated in FIGS. 6A and 6B is shown in detail in United States application Serial No. 681,526 filed September 3, 1957, which application has now been abandoned in favor of United States application Serial No. 724,962, which is a continuation-in-part thereof, and sufficient structure of such time delay or trip device is illustrated in FIG. 6A hereof to show the relationship thereof to the present invention. Also, due to the fact that the time delay or trip device may deliver a somewhat reduced impact as compared to the impact delivered by the dropping of a weight, the tool A has been modi-

fied so that it is balanced with respect to the action of fluid pressure which may be present in the well during the use of the tool A.

With respect to the time trip device, which is particularly shown in FIG. 6A, it has a body or housing 50 which is attached to the body of the tool A so as to form a continuation thereof above the tool A. The body 111 of the tool A as illustrated in FIG. 6B is identical with the body 11 as illustrated in FIGS. 2 and 3, except for certain changes in the bore sizes, as will be explained. The body 50 is formed in several sections, and a central chamber 50a is formed in the body 50. A container 51 having a chemical therein is positioned in the chamber 50a on the upper end of a plunger 52. The container 51 is closed at its upper end by a plug 53 or any other suitable means which is in engagement with a retaining member 54. A spring 55 is an ordinary coil spring and it has its lower end resting on the upper surface of the plunger 52 and its upper end is in engagement with the retaining member 54. A screw 56 which is threaded into corresponding threads 50b engages the upper end of the retaining member 54 to hold the member 54 in a position with the spring 55 under compression and with the lower end of the member 54 in engagement with the plug or closure 53 in the container 51. The plunger 52 is prevented from moving downwardly because of a lock pin 58 extending therethrough and in engagement with a laterally extending inner shoulder 50c on the body 50. The plunger 52 has a seal 60 therewith in sealing engagement with the wall of the bore 50d below the shoulder 50c. The plunger 52 is also preferably provided with an air or gas vent 52a which extends from its lower end to its upper end so that there is fluid communication between the area in the bore 50d below the plunger 52 and the area above the seal 60 in the bore 50a. A plug 61 of any suitable shape may be used for closing the upper end of the opening or passage 52a so as to prevent liquid from flowing through the opening 52a inadvertently. However, the plug 61 is readily removable when a pressure develops in the bore 50d below the plunger 52 upon a downward movement of the plunger 52, as will be more evident hereinafter.

The container 51 is formed of a frangible material such as glass and it holds a chemical which is capable of reacting with the lock pin 58 to dissolve same sufficiently to cause a fracturing or shearing of the pin 58 and a subsequent downward movement of the plunger 52 by the action of the spring 55 forcing the plunger 52 downwardly. Thus, if the pin 15 is, by way of example, an acrylic resin or a polyvinyl acetate resin, as previously stated, then the chemical liquid in the container 51 would be a solvent such as acetone, methyl acetate, ethylene dichloride, monomeric methyl methacrylate, or benzo peroxide. Other materials for the lock pin 58 and the chemicals in the container 51 may of course be used.

The time trip device serves to impart an impact or blow to the impact head or rod 125 which corresponds with the impact head 25 in FIG. 5 of the drawings. In other words, as will be more fully explained, the time delay or trip mechanism as illustrated in FIG. 6A serves to impart a blow or impact to the impact head 125 after a predetermined period of time has elapsed and such blow is transmitted in a manner similar to that explained previously in connection with the dropping of the weight W in FIGS. 1-5. Thus, the impact head 125 transmits the impact to the rod 124 which is in all respects identical with the rod 24 of FIGS. 1-5 except for the lower extension 65 formed therewith for extending through seal 66. It should be pointed out that the impact head or rod 125 also extends through a seal 67, and it is desirable for the diameters of the rod 125 and the lower extension 65 to be substantially the same so that fluid pressure between the seals 66 and 67 does not have any affect on the movement of the rod 124 or the rod 125. Therefore, even though there are fluctuations in the pressure of the

fluid in the well casing or bore, they do not reduce the impact or blow imparted from the time trip device by the downward movement of the plunger 52. The seals 66 and 67 are preferably O-rings made of rubber or similar resilient sealing material. An additional O-ring or other seal 88 is also provided in the body 111 to prevent fluid flow around the packing gland 70. Also, an additional rubber seal 21a (FIG. 1) surrounding the cartridge 21 is preferably provided to prevent fluid from passing to the area of the explosive powder 20 (FIG. 1). In any event, the diameters of the rod 125 and the lower extension 65 should be substantially the same for the equalization of the fluid pressures acting thereon. The changes which result in the housing 111 as a result of the modified impact head 125 and the inclusion of the lower extension 65 as compared to the form of the invention shown in FIGS. 1-5 are believed evident. The rest of the structure in connection with the gripping mechanism which is illustrated in FIG. 6B is identical with that previously described in connection with FIGS. 1-5 and like parts bear the same numerals in FIGS. 1-5 and FIG. 6B.

In the operation or use of the form of the invention shown in FIGS. 6A and 6B, the tool in its complete form is mounted on the flexible line F with the guide sleeves 45 and 46 around the flexible line F, and at that time, the screw 56 is turned inwardly towards the container 51 so as to move the retaining member 54 towards the plunger 52. Such movement places the container 51 under compression and eventually fractures it so that the contents thereof flow downwardly around the upper end of the plunger 52 and contact the lock pin 58. The fluid is of course confined within the chamber 50a and it is a fluid of the type described previously which is capable of dissolving or otherwise weakening the pin 58 so that eventually the spring 55 is capable of forcing the plunger 52 downwardly. Upon a downward movement of the plunger 52, any air or gas which is trapped in the bore 50d below the plunger 52 is permitted to escape through the escape passage 52a. The initial compression of the gas in the bore 50d below the plunger 52 forces the plug 61 out of the passage 52a and thereafter the gas freely flows through the passage 52a as the plunger 52 moves downwardly. The plunger 52 contacts the upper end of the impact head 125 and imparts a downward impact or blow thereto.

It will be understood that there is a sufficient time delay from the initial cracking or fracturing of the container 51 until the lock pin 58 is dissolved or weakened enough for the spring 55 to move the plunger 52 downwardly so that the tool is already at the position for cutting the flexible line F when the lock pin 58 is fractured. In other words, as the tool is being dropped along the flexible line F in the well to its position substantially as shown in FIG. 1 of the drawings, the dissolving or other chemical action between the liquid which is released from the container 51 and the pin 58 is continuing. The amount of time involved before the pin 58 is dissolved or otherwise weakened by the liquid which is released from the container 51 may of course be predetermined by properly selecting the liquid and the material and size of the pin 58.

The blow or impact which is imparted to the impact head 125 by the plunger 52 is transmitted through the rod 124 to the firing pin 22 and then to the firing cartridge 21. The explosion thus takes place as described previously in connection with FIG. 1 of the drawing so as to move the cutter 12 through the flexible line F to cut same. The actuator member 35 is also released as explained in connection with FIGS. 1-5 of the drawings to move the gripping member 14 into gripping engagement with the flexible line F as shown in FIG. 5 of the drawings.

The foregoing disclosure and description of the invention is illustrative and explanatory thereof and various

changes in the size, shape and materials, as well as in the details of the illustrated construction, may be made within the scope of the appended claims without departing from the spirit of the invention.

What is claimed is:

1. A line latch for gripping engagement with a flexible line, comprising a body, a gripping member, pivot connection means mounting said gripping means on said body for pivotal non-longitudinal movement into gripping engagement with the flexible line, an actuator member, means mounting said actuator member on said body for longitudinal non-pivotal movement relative to said body, coacting surfaces on said gripping member and said actuator member for engagement with each other as said actuator member moves longitudinally for urging said gripping member to pivot into said gripping engagement, resilient means for moving said actuator member longitudinally relative to said body, and a releasable retaining means for preventing movement of said actuator member by said resilient means until released.

2. A line latch for gripping engagement with a flexible line, comprising a body, a gripping member mounted on said body for movement into gripping engagement with the flexible line, an actuator member mounted for movement relative to said body for urging said gripping member into said gripping engagement, laterally movable contact means for applying a counteracting force on the flexible line in a direction towards said gripping member, and means for mounting said contact means on said body for lateral movement for applying said counteracting force to prevent the flexible line from moving away from the gripping member as the line is engaged by the gripping member.

3. A line latch for gripping engagement with a flexible line, comprising a body, a gripping member for gripping engagement with the flexible line, means connecting said gripping member to said body for movement relative thereto from a retracted non-gripping position to an extended gripping position in gripping engagement with the flexible line, actuating means for moving said gripping member from the retracted non-gripping position to the extended gripping position, contact means engageable with the side of the flexible line which is opposite from said gripping member, and means operable by said actuating means for moving said contact means in a direction towards said gripping member for preventing the flexible line from moving away from the gripping member as the line is engaged by the gripping member.

4. A line latch for gripping engagement with a line, comprising a body, a gripping member adapted to grip said line, an actuator member longitudinally movable relative to said gripping member for moving said gripping member into gripping engagement with said line, a back-up element extending around the side of the line opposite from said gripping member, a stop member adapted to be engaged by said actuator member, means connecting said stop member to said back-up element for movement together relative to said body, and means for urging said

actuator member longitudinally relative to said gripping member and said stop member for moving said gripping member into gripping engagement with the line and for simultaneously moving the back-up element towards the line to squeeze the line between said back-up element and said gripping member.

5. The structure set forth in claim 4, wherein said actuator member is wedge shaped and is positioned between said gripping member and said stop member for wedging engagement with corresponding wedge surfaces on said gripping member and said stop member when said gripping member is in gripping engagement with the line.

10 6. The structure set forth in claim 4, including pivot connection means for pivotally connecting said gripping member to said body for pivotal movement thereof to thereby obtain substantially lateral movement thereof into gripping engagement with said line.

7. A line latch for gripping engagement with a line, comprising a body, a gripping member adapted to grip 20 said line, an actuator member longitudinally movable relative to said body and said gripping member for moving said gripping member into gripping engagement with said line, said actuating member having a plurality of inclined external surfaces, one of said inclined surfaces 25 being engageable with the inner portion of said gripping member to move same into gripping engagement with said line, and a stop member mounted on said body and having an inclined surface engageable by another of said inclined external surfaces on said actuating member to wedge the actuating member between said stop member and said gripping member when said gripping member is in gripping engagement with said line.

8. A line latch for gripping engagement with a line, comprising a body, a gripping member adapted to grip 35 said line, an actuator member longitudinally movable relative to said body and said gripping member for moving said gripping member substantially laterally into gripping engagement with said line, said actuating member having a plurality of inclined external surfaces, one 40 of said inclined surfaces being engageable with the inner portion of said gripping member to move same into gripping engagement with said line, a stop member mounted on said body and having an inclined surface engageable by another of said inclined external surfaces on said actuating member to wedge the actuating member between said stop member and said gripping member when said gripping member is in gripping engagement with said line, and resilient means for maintaining said actuating member tightly into its wedged position between said stop member and said gripping member.
